UNITED STATES PATENT OFFICE.

WILLIAM BERTRAM BOLLES, OF MILWAUKEE, WISCONSIN.

DOOR-LOCK-OPERATING MECHANISM.

1,280,649.

Specification of Letters Patent.

Patented Oct. 8, 1918.

Application filed January 15, 1916. Serial No. 72,316.

To all whom it may concern:

Be it known that I, WILLIAM BERTRAM BOLLES, a citizen of the United States, residing at Milwaukee, in the county of Milwaukee and State of Wisconsin, have invented a new and useful Door-Lock-Operating Mechanism.

My invention relates to a device adapted to be used in connection with locks for securing doors, and is in the nature of a mechanism which coöperates with a door latch or door lock in such a manner as to permit the latch or bolt to be thrown to such a position as to release the door when the device of my invention is operated. Devices of this character are in the trade known as anti-panic devices, inasmuch as their presence upon the door enables the door to be readily opened by contact with the body of a person falling or pressing against the device, thus preventing any panic in the effort of one or more persons to release the locking mechanism for the door.

Generally speaking, the invention comprises the elements and the combinations thereof set forth in the accompanying claims.

Reference should be had to the accompanying drawings forming a part of this specification in which Figure 1 represents an elevation of my device with the cover removed; Fig. 2 shows the same device in side elevation; Fig. 3 is a plan view, and Fig. 4 is an edge view of the cover for my device; Fig. 5 shows in perspective a lock having an operating lever which is adapted to coöperate with my device.

One object of my invention is to provide a device which may be used in connection or in conjunction with locks that are commercially sold. These locks are adapted to be used substantially with any kind of door, and one purpose of the device of my invention is that it may be conveniently mounted upon any door, and made to coöperate with the lock thereof. The casing which contains a portion of the operating parts of my device is indicated at A, and upon the outside or face of the casing there is mounted a lever B. This lever has an extending portion t which lies in front of the device and of the door upon which the device may be mounted in a position to be readily contacted either by the hand or body of a person who may approach the door. This lever B is mounted pivotally as indicated at U, and has a portion which extends within the casing, the

portion just mentioned extending through a suitable opening in the casing. The portion of the lever B which extends within the casing has pivotally mounted upon opposite sides thereof links C which in turn are pivotally mounted upon a cross piece or pin n. This cross piece has mounted thereon a downwardly extending portion D which is pivotally mounted upon the pin n which pin n also supports the parts K, K'.

Upon the parts K, K', are upwardly extending short pins l which are adapted to engage and center two springs E, E'. These springs at their opposite ends are received upon short posts j which are carried by a bar F, this bar being secured by a threaded screw h which extends through the casing and is threaded into a boss e upon the outside of the casing.

The part D extends through a suitable cut out portion f in the lower portion of the casing A and its engagement with the casing serves in part to guide the part D in its reciprocation as the contact lever B may be operated.

Extending from the member D is a pin q which moves up and down as the contact lever B is operated.

In part the rear of the casing is closed by a cover G which has a slot S formed therein through which the pin q extends. The cover also has an opening r which coöperates with a boss or extension a formed in the casing. This is screw threaded, and a suitable screw g may be inserted through the opening R and screwed into the threaded opening in the boss a.

The device as a whole is applied to a door, and is secured to the door by means of screws which may extend through the opening c at the corners of the casing.

In placing the device upon a door, a slot is cut in the wood of the door through which the pin q may extend and in which it may reciprocate.

In Fig. 5 is shown a form of lock which is commercially sold and this lock is provided with a foot m which is suitably connected with the latch so that as the part m is raised it will cause the latch to be withdrawn from the latch plate with which it normally coöperates when the door is closed.

It is believed that no description of the lock is necessary, inasmuch as the lock is a well known form of lock. However, while the particular lock to which reference is

made has the part or foot *m* which operates the latch, it is obvious that in the broad sense the part *m* may be considered as operating the latch or bolt which coöperates with the latch plate in holding the door in locked position.

The casing *A* is so mounted upon the door upon which the device is to be used, and the slot cut in the door in such fashion that 10 the pin *q* will be in position to coöperate with the foot *m* so that when the contact plate *B* is depressed the pin *q* will engage with the foot *m* and cause the latch to be withdrawn.

15 As the contact plate *B* is pressed the spring *E*, *E'*, will be compressed and as soon as the contact plate *B* is released the springs *E*, *E'*, will act upon the part *K*, *K'*, to push the part *D* down and elevate the contact plate *B*.

20 The two springs and the parts *K* and *K'* act to equalize the force applied to the part *D* when the contact plate *D* is depressed, and furthermore, act to equalize the pressure or 25 force which results in returning the contact plate *B* to its initial or extended position.

Having described my invention, I claim:—

1. In a device of the character described, the combination with a lock having an operating part which moves the locking element of the lock, of a pivoted lever mounted upon the door, a member pivotally connected with said lever and moved by said lever, said member being arranged adjacent to and in operative relation with respect to the lock operating part, a pair of resilient members within the casing disposed upon opposite sides of the said member which engages the operating part of the lock, said resilient members exerting a force to move the said member to its inoperative position.

2. In a device of the character described, the combination of a lock having an operating part which is connected with the locking element of the lock, a pivoted lever mounted upon the door, a member operatively connected with said lever, a pair of resilient members disposed upon opposite sides of the said member, a yoke against which the resilient members bear at one of their ends, and means by which the opposite ends of the

resilient members are operatively connected with the member which coöperates with the lock operating part.

3. In a device of the character described, 55 the combination of a lock having an operating part which is operatively connected with the locking element of the lock, a pivoted lever mounted upon the door, a member operatively connected with said lever, a pair 60 of resilient members disposed upon opposite sides of the said member, a yoke secured within the casing against which one of the ends of the resilient member abut, a cross-member operatively connected with the said 65 member for coöperating with the operating part of the lock, said cross-member having mounted thereon the opposite ends of the resilient members.

4. In a device of the character described, 70 the combination of a lock having an operating part which is operatively connected with the locking element of the lock; a pivoted lever operatively mounted upon the door, a sliding member mounted upon the door, link 75 elements which connect the lever with the said sliding member, a member mounted upon the sliding member adapted to coöperate with the aforesaid operating part which operates the locking element of the 80 lock, and resilient means normally urging the aforesaid slideable member into inoperative position.

5. In a device of the character described, 85 the combination of a lock having an operating part which is connected with the locking element of the lock, a pivoted lever mounted upon the door, a slideable member mounted upon the door, means connecting the slideable member with the pivoted member, said means comprising a cross-pin, resilient members coöperating at one of their 90 ends with the cross-pin, a yoke against which the opposite ends of the resilient members abut, and a member carried by the slideable 95 member coöperating with the operating part which operates the locking element of the lock.

WILLIAM BERTRAM BOLLES.
